ORGAN CABINET

Le Roy J. Ryan, Jr., 5300 W. Hutchinson,
Chicago, Ill. 60641

Filed May 3, 1966, Ser. No. 2,136

Term of patent 14 years

(Cl. D56—2)

FIG.1

FIG.2

FIG.3

FIG.4

FIG. 1 is a front elevational view of an organ cabinet, showing one form of my new design wherein the cabinet is supported on the pedestal by a single column;

FIG. 2 is a left side elevational view of the form shown in FIG. 1, the opposite side being substantially a mirror image thereof;

FIG. 3 is a front elevational view of an organ cabinet, showing another form of my new design wherein the cabinet is supported on the pedestal by two columns; and

FIG. 4 is a rear elevational view of the form shown in FIG. 1.

The side elevational view of the form shown in FIG. 3 is the same as FIG. 2 and the rear elevational view of the form shown in FIG. 3 is the same as FIG. 4 except for the number and position of the columns.

The dominant features of the organ cabinet reside in the portions shown in full lines.

I claim:

The ornamental design for an organ cabinet, substantially as shown and described.
